UNITED STATES PATENT OFFICE.

ORION ARTHUR LITTLE, OF OXFORD, KANSAS.

AUTOMATIC WAGON-BRAKE.

SPECIFICATION forming part of Letters Patent No. 616,058, dated December 13, 1898.

Application filed July 21, 1898. Serial No. 686,501. (No model.)

To all whom it may concern:

Be it known that I, ORION ARTHUR LITTLE, of Oxford, in the county of Sumner and State of Kansas, have invented a new and Improved 5 Automatic Carriage-Brake, of which the following is a full, clear, and exact description.

My invention relates to an improvement in automatic carriage-brakes or brakes which are operated by the team, so as to be applied 10 as soon as the carriage runs forward upon the team.

My invention comprises the novel features hereinafter described and claimed.

Reference is to be had to the accompanying 15 drawings, forming a part of this specification, in which similar characters of reference indicate corresponding parts in all the figures.

Figure 1 is a top plan view of the running-gear of a wagon, showing my brake applied 20 thereto. Fig. 2 is a longitudinal sectional elevation taken through the center of the carriage. Fig. 3 is a side sectional elevation of the mechanism for applying power to the brake; and Fig. 4 is a bottom plan view, partially in section, showing the power mechanism.

The object of my invention is to provide an automatically-operated mechanism to be applied to carriages and wagons, such that the 25 brake will be applied by the mere act of the wagon running forward upon the team. This is accomplished in the manner hereinafter described.

In the drawings one of the rear wheels A 30 of a wagon or carriage is provided with a gear-wheel B, secured thereto. This gear-wheel is not necessarily secured directly to the wheel, but should rotate in conformity therewith. It might in some cases be mounted independently of the wheel, but should be connected 35 with the wheel, so as to rotate therewith. Supported upon the running-gear is a laterally-extending shaft C. This shaft carries a pinion B', meshing with the gear B. Upon 40 this shaft are mounted the two parts of a clutch, the part D being secured to the shaft and the part D' being loosely mounted upon the shaft. When these two parts are placed in engagement with each other, as shown in 45 Fig. 4, they are engaged so as to rotate together. The part D' of the clutch is provided with a groove receiving one end of a link E',

by which the clutch may be engaged while turning. The other end of the link E' is connected with one end of a bell-crank lever F, 55 pivoted at f to the running-gear. At the opposite end of the bell-crank lever F is secured a rod G, which extends longitudinally of the reach R. To this rod is connected a cord or cable G', which extends forward to a connection with the doubletrees. The doubletrees H are mounted upon a plate I, which slides longitudinally of the tongue. By these means it will be seen that a forward pull upon the doubletrees will operate the lever F in such 60 manner as to disengage the two parts of the clutch. The two members of the clutch are ordinarily held in engagement by means of a spring e, which surrounds the shaft C and bears against one end of the part G' of the 70 clutch. Upon the part G' of the clutch is mounted a spool E, to which is secured one end of a cable d. The other end of this cable is secured to the brake-bar K, said brake-bar being mounted upon the running-gear in any 75 suitable manner. This brake-bar is provided with the usual brake-blocks K', adapted to engage the wheels. A spring K² is secured to the brake-beam in such manner as to pull it away from the wheel, and thus to release the 80 brakes.

Upon the plate I, which supports the doubletree, is pivoted a lever J, having a pin O in one end thereof passing downward through a hole in the plate and adapted to engage corresponding holes in the tongue. By these means the plate and the tongue may be locked to each other, so as to prevent sliding. The tongue will be provided with holes so located that the plate may be locked either in its forward or in its rearward position. A sufficient number of holes should be supplied to admit of a small range of adjustment. This lever is ordinarily held upward by a spring J', so as to keep the plate and tongue disengaged. The end of the lever opposite the pin may be connected by a cord or rod J², which leads to a convenient point, where it may be operated by the driver. This will enable the driver to lock the brake from the top of a 90 load of hay or other distant point.

It will be seen that this brake is entirely automatic in its operation, being applied by a forward motion of the wagon and released

by the team pulling forward upon the double-tree. It may also be locked, so as to hold the brake on even when the team is pulling upon the doubletree, by inserting the pin O into one 5 of the rearward holes in the tongue.

Having thus described my invention, I claim as new and desire to secure by Letters Patent—

1. An automatic brake-operating mechanism, comprising a shaft having a gear thereon, an intermeshing gear rotated from a carriage-wheel, a drum loosely mounted on the shaft, a spring-held clutch mechanism adapted to connect the drum with the shaft, a cable fastened to the drum and connected with the brake, and connections from the draft mechanism to the clutch, whereby its parts are separated by the operation of the draft mechanism.
2. An automatic brake-operating mechanism for carriages, comprising a drum having a cable connection to the brake mechanism, means by which the drum may be positively connected to revolve with the carriage-wheel, comprising a spring acting to hold said means in operation, and connections from the drum-operating means to the draft mechanism, whereby the drum is disconnected when the draft is applied.
3. An automatic brake mechanism comprising a shaft having a gear thereon, an intermeshing gear rotated from a carriage-wheel, a drum loosely mounted on the shaft, a spring-held clutch mechanism normally tending to connect the drum with the shaft, a cable fastened to the drum and connected

with the brake; a draft-bar having a sliding mounting, and connections from the draft-bar to the clutch mechanism whereby the clutch mechanism will be released by the forward movement of the draft-bar.

4. An automatic brake mechanism, comprising a shaft having a gear thereon, an intermeshing gear rotated from the carriage-wheel, a drum loosely mounted on the shaft, a spring-held clutch mechanism adapted to connect the drum with the shaft, a cable fastened to the drum and connected with the brake, a draft-bar having a sliding mounting, a locking mechanism therefor normally held out of use, a connection, as a cord, thereto, whereby it may be thrown into use at any time, and connections from the draft-bar to the drum-revolving mechanism, whereby it will be released by the forward movement of the draft-bar.

5. An automatic brake-operating mechanism for carriages, comprising a drum having a cable connection with the brake mechanism, means for connecting the drum and carriage-wheels to revolve together, actuating means for said connecting mechanism normally tending to connect drum and carriage-wheels, a draft-bar having a sliding mounting, and connections from the draft-bar to the mechanism connecting drum and wheels, whereby the drum will be released by the forward movement of the draft-bar.

ORION ARTHUR LITTLE.
